UNITED STATES PATENT OFFICE.

FLOYD C. HEDRICK, OF KENTLAND, INDIANA.

AUTOMATIC FIREARM.

1,249,622.

Specification of Letters Patent. Patented Dec. 11, 1917.

Application filed April 30, 1917. Serial No. 165,453.

To all whom it may concern:

Be it known that I, FLOYD C. HEDRICK, a citizen of the United States, residing at Kentland, in the county of Newton and State of Indiana, have invented certain new and useful Improvements in Automatic Firearms, of which the following is a specification.

My invention relates to improvements in fire-arms, and it consists in the constructions, combinations, and arrangements herein described and claimed.

An object of my invention is to provide an automatically loading fire-arm which includes essentially a magazine for the cartridges, a receiver being mounted upon the gun stock the receiver containing a breech bolt and a firing pin, both of which are adapted to be thrown rearwardly into respective cartridge receiving and cocking positions by the gas pressure incident to the firing of the cartridge.

Another object of the invention is to provide an automatic fire-arm including a gas pressure operated breech bolt and a firing pin disposed within the breech bolt, the breech bolt and the firing pin being provided with actuating springs disposed in such correlation with their respective parts that they are located at a place remote from the firing point of the cartridges so as not to be affected by the heat of firing.

Another object of the invention is to provide an automatic fire-arm having but two moving principal parts consisting of a breech bolt and a firing pin, the breech bolt including an extractor and an ejector whereby an empty cartridge shell is expelled from the gun, the breech bolt serving to receive and insert a fresh cartridge into the bore of the gun.

Other objects and advantages will appear from the following specification, reference being had to the accompanying drawings, in which:

Fig. 1 is a side elevation of a fire-arm illustrating the embodiment of my invention.

Fig. 2 is a plan view of the parts shown in Fig. 1, portions being shown in section.

Fig. 3 is a central vertical longitudinal section of the fire-arm shown in Fig. 1, the firing pin being in the position assumed when a cartridge has been discharged thereby.

Fig. 4 is a cross section on the line 4—4 of Fig. 3 looking in the direction of the arrows, and

Fig. 5 is a cross section on the line 5—5 of Fig. 3 looking in the direction of the arrows.

In carrying out my invention, I provide a gun stock 1 which may be constructed of any suitable material but is preferably constructed of wood as is the usual practice. Mounted on the gun stock 1 is a receiver 2 which has a rearward extension 3 by which the receiver 2 is secured upon the stock 1 through the medium of a pin or bolt 4.

The receiver 2 is hollow and has a longitudinally extending slot 5 at the top. The slot 5 terminates at a relatively large lateral opening 6 through which the cartridges 7 are inserted when it is desired to fill the magazine 8.

As shown in Fig. 3, the magazine 8 is an integral part of the receiver 2 but it should be understood that the magazine 8 may consist of a separate box placed in position on the gun stock 1 and secured in any suitable manner. The present illustration simply defines a method whereby the receiver 2 when once mounted upon the gun stock 1 may be rigidly held in position. In this connection it will be observed that the open bottom of the magazine 8 is closed by a cover plate 9 which is recessed at one end so that the flange or ledge of a trigger guard 10 may be received thereby and secured in position by a screw 11. The trigger guard 10 also includes a rearwardly extending base 12 into which the bolt or pin 4 is threaded and thus binds the correlated parts of the receiver 2 firmly in position on the gun stock 1.

A gun barrel 13 is held in position upon the gun-stock 1 by a number of barrel bands 14. In some instances, it may be found desirable to form the barrel 13 integrally with the receiver 2 but in the present embodiment of the invention, particularly as shown in Fig. 3, the barrel 13 is provided with a threaded male connection 15 which is received by a complementally threaded socket 16 upon the forward end of the receiver 2. The bore 17 of the barrel 13 has an annular chamber or recess 18 at the rear end. The rim 7^a of the cartridge 7 is adapted to be received by the recess or chamber 18 and held in position by the breech bolt 19.

The breech bolt 19 has a collar 20 against which one end of a breech bolt spring 21 is

bears. The other end of the breech bolt spring 21 bears against an annular shoulder 22 of a breech bolt case 23. The breech bolt 19 is slidably mounted in the case 23, 5 the collar 20 and the opening in the annular flange 22 serving to guide the breech bolt 19 in its movement. The breech bolt 19 is thrown backwardly by gas pressure upon the discharge of one of the cartridges 7.

10 A lug 24 on the case 23 is adapted to enter a recess 25 in the edge of the receiver 2 adjacent to the opening 6 as shown in Fig. 1. The purpose of the slot 5 in the receiver 2 will here be apparent, since in assembling 15 the device, the case 23 is inserted into the receiver 2 with the lug 24 in position in the slot 5. When the end of the slot 5 is reached adjacent to the opening 6, the case 23 is turned toward the right until the lug 24 20 comes into registration with the recess 25 when the case 23 is pulled backwardly so that the lug 24 rests in the recess 25 as shown in the drawings.

The rear end of the breech bolt 19 is 25 threaded as at 26 so that a knurled cap 27 may be screwed thereon. The cap 27 has an axial opening 28 in which the shank 29 of a firing pin 30 is slidable.

A spring 31 is coiled about the shank 29 30 and the forward end thereof bears against a collar 32 on the shank of the firing pin. The rear end of the spring 31 bears against an annular shoulder on the cap 27 as shown in Fig. 3. The knurled cap 27 offers a slight 35 range of adjustment for the spring 31 so that should it be desired to increase the tension of the spring 31 somewhat, the knurled cap 27 may be screwed inwardly on the breech bolt 19 and thus tighten the spring 40 31. While the range of adjustment of the spring 31 as represented by the open space in the knurled cap 27 in Fig. 3 is very slight, yet in actual practice, the cap 27 may be so formed that a considerable range of adjustment 45 of the spring 31 may be afforded.

A cocking rod 33 with its coöperating holding devices, serves to retain the firing pin 30 in a retracted position as indicated in dotted lines in Fig. 3. The cocking rod 33 50 has a bracket 34 to which the shank 29 of the firing pin 30 is secured through the medium of a pin 35. A finger piece 36 offers a convenient place to catch the cocking rod 33 when it is desired to draw the firing pin back to a firing position through manual effort.

In the normal operation of the device, the firing pin 30 is retracted or thrown backwardly to the position indicated in dotted lines in Fig. 3, by the recoil of the breech bolt 19. When the firing pin is thus thrown backwardly to its retracted or firing position, it is held in this position by the engagement of a pivoted sear 37 with a notch 60 65 38 in the cocking rod 33. The end of the

sear 37 moves through an opening 39 in the bottom of the receiver 2 as shown in Fig. 3. A sear spring 40' presses the sear 37 into the notch engaging position.

A trigger 40 engages a portion of the sear 37 and when the cocking rod 33 is retracted as above stated and the firing pin 30 is disposed in its firing position, the sear 37 will be in engagement with the notch 38 and depression of the trigger 40 will accordingly 75 release the sear from the notch 38 and permit the firing pin to be impelled forwardly by the tension of the spring 31.

The cartridges 7 are successively moved in line with the bore 17 of the barrel 13 by 80 a follower plate 41 which is pressed upwardly by a spring 42 as clearly shown in Fig. 3. A cartridge 7 is fed upwardly by the follower spring 42 when the breech bolt 19 is thrust backwardly by the gas pressure 85 upon explosion of a cartridge, the end of the breech bolt 19 subsequently engaging the rim 7^a of the cartridge and shoving it forwardly in the bore 17 under tension of the spring 21.

90 An extractor 43 pulls the empty cartridge shell 7 from the bore 17 of the barrel 13 upon the recoil of the breech bolt 19 after the firing of the cartridge. The extractor 43 is secured to the side of the breech bolt 19 at 44 as shown in Fig. 2. The front edge 95 of the extractor 43 is bent at 45 to provide a hook for gripping the rim 7^a of the cartridge 7. The recoil of the breech bolt 19 thus causes the extraction of the empty cartridge shell 7 by reason of the engagement of the hook 45 of the extractor 43 with the rim 7^a of the cartridge shell.

The cartridge shell is then ejected from the gun through the lateral opening 6 by 100 an ejector pin 46 which is fixed upon the receiver 2 and engages a slot 47 at the side of the breech bolt 19. When the breech bolt 19 reaches the extremity of its rearward thrust, the pin 46 will strike the edge of the rim 7^a and the hook 45 of the extractor 43 105 then acting as a fulcrum for the empty cartridge shell 7, will serve to throw the empty shell outwardly through the opening 6 as above stated.

110 The extraction and ejection of an empty cartridge shell is practically simultaneous with the reception and projection into position in the bore 17 of the barrel 13, of a fresh cartridge. It has been explained that the head of the breech bolt 19 presses against the base of the cartridge case and urges it forwardly into its position into the bore 17. It will also be observed that the head of the breech bolt 19 has a central opening 48 which the firing pin 30 enters in striking the cap of the cartridge.

115 The loading of the magazine 8 is accomplished by drawing the breech bolt 19 as far back as it will go and then pressing in 120 125 130

wardly on a breech bolt lock 49 which is so arranged that it will engage the breech bolt 19 and hold it in the retracted position. The lock 49 may consist simply of a spring 5 pressed latch having suitable connection for engaging the breech bolt 19 when the head of the lock 49 is pressed inwardly.

The operation of the device is as follows. The first step in the operation of the automatic fire-arm is to load the magazine 8. This is done by grasping the breech bolt 19 with the fingers of one hand and drawing the breech bolt 19 backwardly against the tension of the spring 21 and then locking 15 the breech bolt 19 in this position through the medium of the breech bolt lock 49.

The cartridges 7 are then inserted into the magazine 8 through the lateral opening 6. When the lock 49 is now released the 20 breech bolt 19 will move forwardly and carry a cartridge 7 with it and project the cartridge 7 into its position in the bore 17 of the barrel 13. The act of drawing the breech bolt 19 also causes the firing pin 30 25 with its shank 29 to move rearwardly until the notch 38 in the cocking rod 33 is moved into registration with the end of the sear 37. The cocking rod 33 is consequently engaged by the end of the sear 37 through 30 the effort of the sear spring 40'. It will thus be understood that the loading of the magazine 8 and the projection of the first cartridge 7 into position into the bore 17 of the barrel 13 is by manual effort. When the 35 trigger 40 is now depressed and the sear 37 released from the notch 38 in the cocking rod 33, the firing of the cartridge 7 results by reason of the expansion of the spring 31 against the collar 32.

40 The recoil of the breech bolt 19 which results by the firing of the cartridge 7 serves to bodily move the breech bolt 19 rearwardly and carry the firing pin with its cocking rod 33 therewith. The recoil referred to is 45 sufficient to carry the notch 38 into registration with the end of the sear 37 which will accordingly engage the notch and hold the cocking rod 33 and firing pin 30 in readiness for a subsequent discharge of another cartridge.

50 It has been explained that the rearward movement of the breech bolt 19 through the impetus of the gas pressure causes the extraction of the empty cartridge shell through the medium of the extractor 43. It has also been explained that the empty cartridge shell 7 is ejected by means of the pin 46 which moves in the slot 47. Almost simultaneously with the extraction of the empty 55 cartridge shell, a fresh cartridge 7 is urged upwardly into position against the head of the breech bolt 19 by the follower spring 42. When the effort of the recoil ceases, the breech bolt 19 will again move forwardly 60 through the exertion of the tension of the 65

spring 21 in the case 23. The fresh cartridge 7 which was previously advanced in front of the head of the breech bolt 19 by the follower spring 42, is now carried forwardly and projected into its position in 70 the bore 17 of the barrel 13.

Upon each firing of a cartridge 7, the 75 ejection of the empty cartridge shell and the reloading of the barrel of the gun is an automatic action. While but two cartridges are illustrated in the cartridge magazine 8, it should be understood that the magazine 8 may be of any desired length so that a comparatively great quantity of 80 cartridges may be carried thereby.

It should also be observed that the construction of the automatic fire-arm involves the least number of mechanical parts. The arrangement is such that any one can readily be replaced and the repair of the fire-arm is 85 a comparatively simple matter when the mechanisms of other fire-arms are taken into consideration.

In designing the fire-arm, the endeavor has been made to so locate the springs 21 90 and 31 that they are disposed remotely from the firing point of the cartridges. Obviously by locating the springs 21 and 31 at a place remote from the firing point, the temper of the springs will not be affected. 95

While the construction and arrangement of the device as illustrated in the accompanying drawings is that of a generally preferred form, obviously modifications and changes therein may be made without 100 departing from the spirit of the invention or the scope of the claims.

I claim:—

1. A fire-arm including a barrel, a receiver including a magazine and having a 105 longitudinal slot and a lateral discharge opening, the receiver having a notch adjacent to the discharge opening, a recoil operated breech bolt for receiving and pressing a cartridge toward and into the barrel, and 110 a breech bolt case for supporting the breech bolt, said case having a lug receivable within the notch for fixing the case in position.

2. In a fire-arm, the combination of a barrel, a receiver, including a magazine, said receiver having a lateral discharge opening, said receiver having a notch adjacent said discharge opening, a breech bolt case positioned within said receiver and having a lug carried within said notch for holding said 115 case in a set position, a breech bolt reciprocally mounted within said case, a collar carried upon said breech bolt, a coil spring bearing upon said case and said collar for urging said bolt in one direction, a firing pin having a shank projecting through said breech bolt, a coil spring carried within said breech bolt for urging said firing pin in one direction, said breech bolt and firing pin being thrown rearwardly by gas pres- 120 125 130

sure, and means for releasably retaining said firing pin in a set position and said breech bolt returning to its normal position.

3. In a fire-arm, the combination of a barrel, a receiver, a breech bolt case carried by said receiver, a cylindrical breech bolt projecting through said casing, a collar formed upon said breech bolt, a coil spring bearing upon said collar and carried within said 10 casing for urging said breech bolt in one direction, a cap carried upon one end of said breech bolt, an opening formed in the opposite end of said breech bolt, a firing pin projecting through said last mentioned opening, 15 a shank connected to said firing pin and extending into said cap, a spring bearing upon said cap, a collar carried upon said shank, said last mentioned spring engaging said last mentioned collar for urging said firing 20 pin in one direction, an L shaped cocking rod connected to said shank and extending into said receiver and said casing, said breech bolt and firing pin being moved rearwardly by gas pressure, means engaging said cocking rod for releasably retaining the same in 25 a set position and said breech bolt returning to its normal position.

4. In a fire-arm, the combination of a barrel, a receiver, including a magazine, said 30 receiver having a lateral discharge opening, said receiver having a notch adjacent said opening, a breech bolt casing carried within said receiver and having a lug fitting within

said notch for holding said case in a set position, a breech bolt passing through said casing, a collar formed upon said breech bolt and engaging the inner surfaces of said casing whereby said breech bolt will be held in a central position, a coil spring carried within said casing and bearing upon said collar for urging said breech bolt in one direction, said breech bolt having an opening in one end and a cap upon the opposite end thereof, a shank having a firing pin upon one end, a collar carried by said shank, said collar bearing within said breech bolt and said shank passing through said cap, whereby said firing pin will be held in alignment with the opening in said breech bolt, a coil spring carried within said breech bolt and bearing upon said last mentioned collar for urging said firing pin in one direction, an L shaped cocking rod connected to said shank and fitting between said case and receiver, said breech bolt and firing pin being thrown rearwardly by gas pressure, means for releasably engaging said cocking rod and holding said firing pin in a set position, and said breech bolt returning to its normal position.

In testimony whereof I affix my signature in presence of two witnesses,

FLOYD C. HEDRICK.
